(57) **CLAIM**

The ornamental design for flexible headset for sensing brain electrical activity, as shown and described.

DESCRIPTION

FIG. 1 is a front perspective view of a flexible headset for sensing brain electrical activity showing our new design;
FIG. 2 is a front view thereof;
FIG. 3 is a back view thereof;
FIG. 4 is a top view thereof;
FIG. 5 is a bottom view thereof;
FIG. 6 is a left side view thereof; and,
FIG. 7 is a right side view thereof.

Circuit traces and other conductive features forming portions of the article not shown form no part of the claimed design. The broken lines are included for the purpose of illustrating portions of the flexible headset for sensing brain electrical activity that form no part of the claimed design.
